UNITED STATES PATENT OFFICE.

SAMUEL EVANS, OF TORONTO, ONTARIO, CANADA.

COMBINED PENCIL-SHARPENER AND POCKET-CLIP.

1,185,387.

Specification of Letters Patent. Patented May 30, 1916.

Application filed May 22, 1914. Serial No. 840,265.

To all whom it may concern:

Be it known that I, SAMUEL EVANS, a subject of the King of England, residing at Toronto, in the Province of Ontario and 5 Dominion of Canada, have invented new and useful Improvements in Combined Pencil-Sharpener and Pocket-Clips, of which the following is a specification.

The invention has for an object to enable 10 the ready formation of a pencil clip for holding the edge of a pocket or the like pressed closely against the side of a pencil, and in the same device to provide a blade mounting which may be positioned to permit sharpening 15 of the point of the pencil upon which it has been previously used as a clip, without requiring removal of the device from the pencil.

An important purpose is to enable the 20 manufacture of the device from sheet metal.

Another important object is to provide an efficient means for pivoting a swinging blade carrier and clip arm on a pencil guiding sleeve, and to provide efficient means for 25 quickly fixing the arm at opposite limits of its movement.

Additional objects, advantages, and features of invention will appear, some of which will be apparent in the construction, 30 arrangement, and combination of parts hereinafter set forth and shown in the drawings, in which—

Figure 1 is a side view of one embodiment 35 of my invention in use as a clip; Fig. 2 is a view showing it in use as a sharpener; Fig. 3 is a cross section showing the pivot socket; Fig. 4 is a similar view showing the latch construction; Fig. 5 shows the device 40 in a pocket; Fig. 6 is a rear view; Fig. 7 is a side view of a modification; Fig. 8 is a cross section showing one blade mounting; Fig. 9 is a similar view showing a different blade structure.

There is illustrated a pencil engaging 45 sleeve 10 formed of sheet metal and having the bead 11 around each end. The sleeve is shown to be cylindrical, although that is not essential, and at what will be termed the top is provided with outwardly struck lug portions 50 12 forming in effect a socket to receive snugly a ball 13 formed on the inner end of an arm 14 to be described. This arm is properly attenuated at its point of connection with the ball forming a neck 15. The 55 arm is formed of sheet metal and may have

edges inturned to reinforce the neck 15, as shown. Immediately outward of the neck 15 two spring fingers 16 are formed at opposite sides of the arm shaped to press in closely around the sleeve 10 and hold the 60 arm closely down thereagainst or close thereto. To make this action more certain, the sleeve is longitudinally slotted as at 17 and 18 adjacent respective ends, the upper sides 65 of the slits being pressed outwardly to form bills 19, the fingers 16 being similarly slotted and their lower portions pressed inwardly to form bills 20 to hook under those 19 at the opposite limits of adjustment of the arm 14. The fingers 16 have their outer ends 70 turned out a little to enable their manual disengagement from the bills on the sleeve when necessary. The arm 14 is broadened immediately outward of the fingers, and beginning 75 closely adjacent the fingers there are formed wings 21 gradually enlarged toward the outer part of the arm but curving abruptly inward at their edges as at 21' a distance from the end of the arm, from whence the arm is continued in a tapered 80 clip finger 22 having the usual ball 23 at the outer end. Between the wings there is formed a central longitudinal slit 24 stopping short of the inwardly inclined edges 21' of the wings, and beginning near the end of the 85 sleeve 10 when the arm 14 is in what may be termed outer or sharpening position. Lateral short slits 24' are formed at each end of the slit 24, on one side, and the intervening edge portion of the metal is 90 pressed inwardly and sharpened to form a blade 25. If desired, however, a separate blade may be inserted and secured in any well known manner familiar in pencil sharpeners such as indicated in Fig. 8. Here, a 95 flange 25^a is pressed outwardly from the central part of the arm 14, the outer part of the flange being turned inward at a right angle, and a blade 25^b set and soldered in the angle thus formed. In the event that the blade is 100 formed integrally I consider it desirable that the edge be ground principally on the outer side, but also ground sufficiently on the inner side to give a rectilinear edge. The grinding of the outer side may be accomplished by pressing the working edge outwardly sufficiently for the purpose, the blade being subsequently pressed inward as desired.

It should be observed that the slits 18 at 110

the outer end of the sleeve are nearer the lower side of the sleeve than are the slits 17. The arm 14 is so formed that it tends to spring inward and extend across the axis of the sleeve at an oblique angle when the tongues are engaged with the outer bills 19, whereby the blade 25 is so disposed that when the end of a pencil is presented in the sleeve and forced outwardly against the blade, then rotated, it will be sharpened, as indicated in Fig. 2. When the fingers are disengaged—which may be done by prying one outward, then swinging the arm 14 outward in the direction of the other and lifting it—the arm may be rotated on its axis and moved pivotally until the fingers may be forced downward over the opposite end of the sleeve 10. When a pencil is engaged in the sleeve, this will force the outer end of the clip against the side of the pencil with proper force to serve in holding the edge of a pocket when slipped under the clip. When the device is so engaged, the inwardly inclined edges of the wings 21 engage against the upper edge of the pocket, and prevent it from passing beneath the blade 25, so that no damage will occur. The blade is also held slightly away from the surface of the pencil, so that in adjustment of the sleeve longitudinally, or other movement of the pencil in the sleeve, the blade will not be dulled.

In use, the device may be kept upon the pencil at all times, and when the arm 14 is moved from one position to the other, it will snap into locked position by a slight pressure on the outer side.

It will probably be found desirable to form a round opening 27 at each end of the blade 25 in order to reduce liability of cracking of the metal at the base of the blade, and also reduce liability of jamming of shavings.

In Fig. 7 there is shown a modification in which the necessity for an extension of the arm 14 beyond the blade is obviated, and the blade carrying portion of the arm is adapted to receive the edge of a pocket thereunder without liability of damage. In this case the sleeve may be formed as above described, and the arm 14^a pivoted in the same way as the arm 14, or, the inner end of the arm may be provided with a longer attenuation 15^a pivoted by a rivet engaged through its extremity and in the sleeve, the length of the attenuation permitting the arm to be flexed to allow the fingers 16 to clear the sleeve when moved from one position to the other. The fingers and outwardly adjacent portion of the arm are formed as before described, but the wings 21^a are tapered rapidly to the ball 23^a, which in this case, it should be noted, is formed quite large, so that when a pocket edge is engaged thereunder against a pencil, the blade will be held outwardly and away from the fabric, so that it will not

be cut. This form of the outer part of the arm may be found preferable to that first described.

The simplicity and desirability of the device will be apparent, and the adaptation of the spring clip arm to also carry the blade and move inward at times to enable the sharpening of a pencil represents a very desirable improvement of function in such devices.

What is claimed is:

1. A device of the class described comprising a pencil engaging member, a clip member carried thereby comprising a resilient arm adapted to bear at its outer part against the side of an engaged pencil at times for the purpose described, said clip member having a blade on its inner part thereon and being positioned and constructed to lie farther inwardly at other times, with relation to the pencil engaging member, to present the blade in the path of a pencil extended through the pencil engaging member.

2. A device of the class described comprising a pencil engaging member, an arm pivotally carried thereon, movable to project longitudinally over opposite ends of the member alternatively, means to fix the arm releasably at the opposite positions, and located to hold the arm at a greater angle to the axis of the pencil engaging member at one end than at the other, a blade carried by the arm, and a fabric engaging device on the arm outwardly of the blade.

3. A device of the class described comprising a cylindrical sleeve open clear at each end, a movable arm thereon, a blade on the inner part of the arm, means to releasably fix the arm in position inclined inwardly over one end of the sleeve at times to receive a pencil end against the blade, means to releasably fix the arm at a lesser angle over an end of the sleeve to bear against the side of a pencil engaged through the sleeve, and a fabric engaging device on the arm outwardly of the blade.

4. A device of the character indicated comprising a cylindrical sleeve open clear at each end, an arm pivoted thereon for movement to project from opposite ends of the sleeve alternatively, said arm having opposite lateral fingers constructed to bear against the sides of the sleeve, coengaging devices formed on the fingers and sleeve for holding the arm releasably fixed at opposite positions on the sleeve, a blade carried by the arm, and a clip device thereon.

5. A device of the character described comprising a cylindrical sleeve, an arm pivoted thereon for movement to project from either end of the sleeve, resilient fingers on the arm to embrace the sleeve, oppositely extended bills formed on the fingers and sleeve at each side adapted to coengage

to prevent upward movement of the arm, the bills at one end of the sleeve being lower than those at the other, and an intermediate located blade on the arm.

- 5 6. A device of the character described comprising a pencil engaging member, an arm carried thereby movably mounted and constructed to lie at different angles to the axis of the sleeve and inclined inwardly
10 over the end of the sleeve, a blade carried by the arm intermediately of the ends of the

arm, a clip extension on the arm outwardly of the blade, and wings on the arm to engage the edge of a fabric inserted beneath the clip.

15

In testimony whereof I have hereunto set my hand in presence of two subscribing witnesses.

SAMUEL EVANS.
